THE COLUMBIA PLANOGRAPH CO., WASHINGTON, D. C.

UNITED STATES PATENT OFFICE.

ISAAC TROLLEY, OF POUGHKEEPSIE, NEW YORK, ASSIGNOR TO MOLINE PLOW COMPANY,
A CORPORATION OF ILLINOIS.

MOWING-MACHINE.

1,318,418.

Specification of Letters Patent.

Patented Oct. 14, 1919.

Application filed October 14, 1916. Serial No. 125,547.

To all whom it may concern:

Be it known that I, ISAAC TROLLEY, a citizen of the United States, residing at Poughkeepsie, in the county of Dutchess and State 5 of New York, have invented certain new and useful Improvements in Mowing-Machines, of which the following is a specification, reference being had therein to the accompanying drawing.

10 This invention relates to mowing machines and has reference more particularly to the lever mechanism for raising and lowering the cutter bar, and to the means for operating the clutch controlling the cutting mechanism.

15 The invention consists of a lever mechanism and coöperating clutch controlling mechanism of improved form and construction by means of which, in the raising and 20 lowering movements of the cutter bar, the clutch will be automatically controlled.

25 The invention consists also, in combination with said mechanism, of a foot operated mechanism of improved form and construction 30 operable to effect the elevation of the cutter bar to a limited extent without disconnecting the clutch.

35 The invention consists also of improved foot operated means coöperating with the 40 clutch controlling means and operable to disconnect the clutch without raising the cutter bar.

45 In the more specific embodiment of my invention, the lever mechanism for raising and lowering the cutter bar, is in the form 50 of a hand lever operatively connected with the cutter bar so that by the operation of the hand lever the cutter bar will be respectively raised and lowered, the said lever having 55 connected with it a cam adapted to coöperate with a shifting clutch-controlling member, the said parts being so relatively formed and constructed that by the operation of the hand lever in one direction the clutch will be disconnected, and by the operation of the 60 hand lever in the opposite direction the clutch will be connected, the clutch controlling member being capable of a movement relatively to the operating cam on the hand lever, so that the clutch may be operated independently of the hand lever and without raising the cutter bar. The connections between the hand lever and cutter bar are capable of a movement relatively to the 65 hand lever and the clutch controlling mem-

ber so that the driver by his foot may raise and lower the cutter bar without disconnecting the clutch.

In the accompanying drawings:

Figure 1 is a side elevation partly in section of a mowing machine having my invention embodied therein, the near wheel being omitted.

Fig. 2 is a top plan view on an enlarged scale, with parts in section and other parts broken away to better illustrate the mechanism.

Fig. 3 is a side elevation partly in section of the clutch controlling mechanism.

Referring to the drawings:

1 indicates the frame of the machine in which is rotatably mounted a horizontal axle 2, to the ends of which are loosely applied, ground wheels 3 clutched as usual to the axle so that the latter will be rotated in 75 the forward movement of the machine, but when the machine is backed the ground wheels will rotate freely on the axle.

Sustained by the frame of the machine at the front is the usual cutter bar 4 connected 80 at its inner end with the frame in such manner that the cutter bar may be swung up and down about a fore and aft horizontal axis.

The knife rod of the cutting mechanism 85 receives its motion from the ground wheels, by means of the usual driving pitman 5 connected at its outer end with the knife rod and connected at its inner end with a crank disk 6 on the forward end of a horizontal 90 fore and aft extending driving shaft 7 journaled in the frame of the machine and provided at its rear end with a bevel pinion 8. The bevel pinion 8 is engaged by a bevel gear 9 mounted loosely on a horizontal 95 transverse counter-shaft 10 journaled in bearings in the frame, which counter-shaft has on one end a spur pinion 11 engaged by an internal gear 12 keyed to the axle 2. Bevel gear 9 is provided with clutch 100 teeth with which coöperate clutch teeth on a clutch member or hub 12^a splined to the counter-shaft, so that by shifting the clutch member in opposite directions, the teeth may be engaged or disengaged with each other, 105 and in this manner the operation of the drive shaft 7 and consequently the actuation of the knife rod will be controlled.

The clutch member 12^a is shifted by means of a shifting fork 13 carried on a rod 13^a 110

mounted to slide endwise in a guide 13^b on the frame of the machine, the rod being encircled by a spiral spring 14 bearing respectively against the fork and the end of the 5 guide and tending to maintain the clutch connected.

The rod 13^a is shifted endwise in a direction to disconnect the clutch by means of a clutch operating member in the form of a 10 curved slotted arm 15 projecting rearwardly from an upright lever 16, the lower forward end of which lever is fixed to a horizontal transverse rock shaft 17 mounted in bearings in the machine frame and provided at 15 one end with a crank arm 18, the purpose of which will presently appear. The end of the rod 13^a extends through the slot in the curved arm 15 and it is provided on its extremity with a head 19 bearing against the 20 side of the arm, the opposite side of which bears against the end of the guide 13^b. The side of the arm 15 which engages the head 19 is beveled at its lower portion to form a cam surface 20, and above this cam surface 25 the two sides of the arm are parallel to each other, the result being that when the arm is swung down by the rocking of shaft 17, the cam surface engaging the head 19 will shift the rod and place the spring 14 under tension and disconnect the clutch, and when the arm is swung upwardly, the spring on rod 13^a will be permitted to react and will connect the clutch.

The foregoing mechanism constitutes one 35 form of clutch for controlling the driving means between the ground wheels and the cutters, which mechanism, except in respect to the clutch operating member and the manner of operating the same as will be 40 more fully described hereinafter, forms no part of the present invention.

Mounted loosely on a horizontal stud 21 fixed in the framework of the machine, is a 45 rocking lever 22 having a forwardly extending arm 23 and a rearwardly extending arm 24. The forward arm has pivoted to it, the upper end of a link 25, the lower end of which is operatively connected with the cutter bar in such manner that when the link 50 is lifted, the cutter bar will be swung upwardly on its axis, and when the link is lowered the cutter bar will be likewise lowered. The rear arm 24 of this lever is provided with a vertical slot 26 in which engages a pin 27 on the forward end of a rod 28, which rod extends rearwardly and has its rear end pivoted as at 29 to a vertical foot lever 30. The lower end of the foot lever is pivoted as at 31 to the machine frame 55 and at its upper end it is provided with a pedal 32 to be operated by the driver's foot. The driver occupying the driver's seat X, may by pushing forward on foot lever 30, rock the lever 23 on the stud 21 in a counter- 60 clockwise direction, which will swing the 65

forward arm 23 upwardly and raise the link 25 and the cutter bar will be swung upwardly on its axis.

This mechanism constitutes a means for lifting the cutter bar to a limited extent 70 without affecting the driving connection to the cutters, and is employed by the driver for quickly and momentarily elevating the cutter bar a short distance to avoid irregularities or obstructions in the surface of the 75 ground while the cutters are still in action.

Also loosely mounted on the stud 21 along side the rocking lever 22 is a hand lever 33 which normally when the cutter bar is down and in operative position, extends vertically 80 as shown in Fig. 1, and bears at its rear edge near its lower end loosely against a lug 34 on the rocking lever 22 so that when the hand lever is pulled to the rear, it will by 85 engaging lug 34 rock lever 22 in the same manner that it was rocked by the foot lever 30 as before described, with the result that the cutter bar will be elevated. The lever 33 is provided with a locking latch adapted to coöperate with notches 35, 35^a and 35^b 90 in a segment frame 36 fixed to the machine framing, these notches being so located that the lever may be locked either in a vertical position with the cutter bar down, or in a rearwardly inclined position (as shown by 95 dotted lines in Fig. 1) with the cutter bar elevated to its full extent or in an intermediate position with the cutter bar partially raised and clutch disconnected. The purpose of this lever is to effect the full elevation 100 of the cutter bar to a vertical position, and mechanism is provided, actuated by the lever, for controlling the clutch operating means in such manner that when the lever is pulled to the rear to elevate the cutter bar, 105 the clutch controlling the operation of the cutters will be thrown out of action, and when the lever is pushed forward to lower the cutter bar the clutch will be again thrown into action.

This mechanism comprises a clutch controlling member in the form of a horizontally shifting frame 37, shown more particularly in Fig. 3, which is actuated by a vertical cam 38 fixed to the lower end of the 110 hand lever 33 and extending downwardly below the stud 21. The shifting frame 37 is suspended so that it will shift horizontally forwardly and rearwardly, by means of an upright suspension link 39, the upper end 115 of which is provided with a lateral journal 40 loosely mounted in the frame of the machine while its lower end is provided with a horizontal journal 41 mounted loosely in a bracket 42 depending from the shifting frame, the construction being such that the shifting frame may be swung from its rear position as indicated by full lines in Fig. 3, to a forward position as shown by dotted lines in said figure. The shifting frame has 120

130

connected with its rear end a rod 43 which extends rearwardly and is provided at its rear extremity with an eye 44 mounted on the crank arm 18 on the rock shaft 17 before alluded to. As a result of this construction and arrangement of the parts, when the shifting frame is shifted forwardly, the crank shaft will be rocked counter-clockwise and will swing the clutch operating arm 15 downwardly and disconnect the clutch, the shifting of the frame in the opposite direction to its former position, causing the clutch operating arm to swing upwardly and permitting the spring to again connect the clutch, these movements of the frame being effected and controlled by the cam 38 on the hand lever 33, in the manner now to be described.

The shifting frame contains a vertical slot 37^a extending longitudinally therethrough from end to end, in which slot the cam 38 will extend in the operation of the hand lever. In the forward end of the slot a detent 45 is loosely mounted on a horizontal pivot pin 46 which detent is provided with a forwardly extending horizontal finger 47, with a rearwardly extending horizontal finger 48 and with a downwardly extending finger 49. An expansion spring 50 is seated between the finger 49 and the end of the block and tends to hold the detent with its finger 47 in engagement with a stop 51 on the block and with the finger 48 in a horizontal position. A second detent 52 is pivoted on a horizontal pivot pin 53 at the rear end of the slot, which detent is provided with a forwardly extending finger 54 and with a depending finger 55, an expansion spring 56 being seated between the finger 55 and a lip 56^a on the rod 43, which spring tends to hold the detent with the finger 54 in a horizontal position with a stop shoulder 57^a thereon in engagement with a stop lug 58 on the frame.

The cam 38 before alluded to is provided with a toe 59, with a heel 60 and with an intermediate tooth 61, these parts being of such form and being so related to the two detents, that when the hand lever 33 is pulled to the rear to elevate the cutter bar, the toe 59 will engage the finger 48 of the forward detent and will shift the frame forwardly and thereby actuate the clutch operating arm 15 and effect the disconnection of the clutch; and when the lever is pushed forwardly to lower the cutter bar, the heel 60 of the cam will engage the finger 54 of the rear detent and will shift the frame to the rear and thereby actuate the clutch operating arm and disconnect the clutch, the tooth 61 on the cam serving, by engaging the end of finger 48 on the forward detent, to hold the frame forward with the clutch disengaged, in which position of the parts they are locked by the engagement of the locking

latch on the hand lever in the intermediate notch 35^a in the segment frame.

The operation of the parts to effect the foregoing actions is as follows: In the normal position of the parts with the cutter bar in a horizontal operative position, the shifting frame 37 will be in its rear position, the clutch operating arm 15 will be in its raised position with the clutch connected, the hand lever 33 will be in a vertical position and locked by the engagement of its latch in notch 35 in the segment frame, and the cam on the lever will be in its rear position with the toe 59 some distance in rear of finger 48 on the forward detent. When now the cutter bar is to be raised, the driver unlocks the hand lever from the segment frame and pulls the lever to the rear. The first portion of the rear movement of the lever will swing the cam 38 forwardly and will simultaneously start the raising motion of the cutter bar, this movement of the cam continuing until the toe 59 brings up against finger 48 of the forward detent. The cutter bar is now partially raised and the clutch still connected, this partial elevation of the bar not being sufficient to cause any binding on or interference with the action of the operating pitman for the knife rod, so that the cutting mechanism will still be operative. The knives are therefore enabled to cut higher from the surface of the ground than when the cutter bar is in a horizontal position, which abnormal action of the cutting mechanism is desirable under certain conditions encountered in the operation of the machine in the field.

As the hand lever is moved farther rearwardly, the toe 59, by engagement with the finger 48 of the forward detent will positively shift the frame 37 forwardly, which action will rock the rock shaft 17 and will swing the clutch operating arm 15 downwardly and effect disconnection of the clutch, this position of the parts being represented by the dotted lines in Fig. 3, where it will be seen that the toe on the cam is just passing beyond the end of the finger and disengaging from the finger. In the movement of the cam just described, and due to the forward shift of the shifting frame, the finger of the rear detent is brought in the path of the heel of the cam and the rear detent is rocked downwardly on its axis by the heel so that the cam is permitted to continue its motion without interference with the rear detent. The clutch is now fully disconnected but the cutter bar only partially elevated. The parts may be locked in this position by engagement of the latch on hand lever in intermediate notch 35^a. In the third and final period of the rear movement of the hand lever, the edge of the cam in rear of the toe moves along the rear finger of the

forward detent and the tooth 61 on the cam brings up against the finger, this movement continuing the elevation of the cutter bar but not affecting the position of the frame 37, and as the movement of the lever continues still farther, the tooth 61 pushes on the finger 48 of the forward detent and shifts the frame 37 to a still farther position forwardly, thus completing the final 10 elevation of the cutter bar to its vertical position and causing the clutch operating arm to swing still farther downwardly with the parallel sides of the arm sliding between the head on the rod 13^a and the end of the guide for said rod. The hand lever is now locked to its segment frame in the lower notch therein, in which position the tooth 61 is engaged with the finger of the forward detent and therefore the shifting frame is locked in its forward extreme 20 position with the clutch disengaged.

When the cutter bar is to be lowered again into action, the hand lever is unlocked and pushed forwardly. In the first 25 period of this movement, the cam in moving rearwardly, will disengage the tooth from the forward detent and the heel of the cam will be brought into engagement with the finger of the rear detent, the movement of the cam thus far being attended by the partial descent of the cutter bar from its vertical position and the shifting frame being undisturbed. As the hand lever now continues to move forward, the 30 heel of the cam engaging the rear detent will shift the frame rearwardly, thereby rocking rock shaft 17 in a clockwise direction and swinging the clutch operating arm 15 upwardly from its lowest position, the parallel sides of the arm sliding between the head on the rod 13^a and the guide 13^b and therefore maintaining the clutch disconnected. As the cam moves still farther rearwardly on the continued forward movement of the hand lever, the heel maintaining engagement with the rear detent will shift the frame farther and swing the clutch operating arm still higher, thereby carrying the cam surface 20 along the side 35 of the head on rod 13^a and releasing the rod and permitting its spring 14 to shift the clutch member and connect the clutch, the rear movement of the cam and forward movement of the lever continuing until the lever is in a vertical position where 45 it is locked with the clutch operating arm fully raised, as shown in Fig. 3. In the foregoing movement of the parts, the toe of the cam engages the upper side of the finger on the forward detent and the latter is swung downwardly on its axis and in this manner permits the cam to be moved to the rear without interference with said detent. The cutter bar is now lowered to 60 its final horizontal position and the cam is

in the position shown in Fig. 3, where it will be seen that the toe extends in the slot in the block midway between the fingers on the two detents so that the block is free to be moved independently of the 70 cam and connected parts.

Advantage is taken of this condition of the block to permit the clutch to be disconnected without elevating the cutter bar, since in practice it is sometimes desirable to 75 stop the operation of the cutters independently of the automatic disconnection of the clutch effected by the elevation of the cutter bar. This independent operation of the clutch is effected through the medium 80 of the lever 16 before alluded to as carrying the clutch operating arm 15, the upper end of the lever being provided with a foot pedal 63, so that the driver by pressing downwardly thereon may swing the clutch 85 operating arm downwardly and throw the clutch out of action. In this action of the arm the shaft 17 will be rocked in a counter-clockwise direction and the shifting frame 37 will be shifted forward idly. 90

Owing to the fact that when the cutter bar is in raised position, the tooth 61 on the cam bears against the finger of the forward detent, the frame 37 will be locked in its forward position, hence there will be 95 no danger or liability of the inadvertent operation of the lever 16 by the driver to connect the clutch.

Due to the form of the clutch controlling mechanism described, the cutter bar is raised 100 some distance before the clutch is thrown out, the extent of elevation of the cutter bar not being such as to interfere with the proper operation of the knife rod by the driving pitman, and such elevation of the 105 bar with the cutting mechanism operative being desirable in order to act on the grass farther from the surface of the ground than under normal conditions. Also due to the form of my improved clutch controlling 110 mechanism, the elevation of the cutter bar is continued after the clutch has been disconnected, so that it may be raised to its full and extreme vertical position without interference with or complications by the connections to the clutch, the disconnection of the clutch in the elevating action of the cutter bar, taking place at the same point in the movement of the bar as the connection of the clutch takes place when the cutter bar is 115 lowered. It will be seen, therefore, that by my improved mechanism I provide means, controlled by the foot lever 30, for raising and lowering the cutter bar to a limited extent without interfering with the action of the cutters, which operation of the parts is desirable in avoiding obstructions and irregularities in the surface of the ground. Also I make provision, by means of the foot lever 16, for disconnecting the clutch and 120 125 130

stopping the operation of the cutting mechanism without elevating the cutter bar; and also by the hand lever 33 and the clutch controlling mechanism operated thereby, I provide for the full and complete elevation of the cutter bar and automatically effect the disconnection of the clutch on the elevation of the bar, and the reconnection of the clutch when the bar is again lowered into action.

10 In the foregoing description and accompanying drawings, I have set forth my invention in the particular detailed embodiment which I prefer to adopt, but it will be manifest that the details may be variously 15 changed and modified without departing from the limits of my invention; and it will be understood that the invention is not limited to any particular form or construction of the parts except in so far as such limitations are specified in the claims.

Having thus described my invention, what I claim is:

1. In a mowing machine, the combination of a main frame, a cutter bar hinged thereto 25 to swing upwardly, driving mechanism for the cutters including a clutch, a hand lever pivoted on the main frame and operatively connected with the cutter bar for raising and lowering the same, a clutch operating 30 mechanism including a frame shiftable in opposite directions to respectively disconnect and connect the clutch, opposing detents on said frame, a member movable with the lever and in position to engage one of said 35 detents and shift the frame in one direction to disconnect the clutch, and a second member movable with the lever and in position to engage the other detent and shift the frame in the opposite direction to connect the 40 clutch, said detents being yieldable in one direction to permit one member to pass its associated detent when the other member acts on the other detent.

2. In a mowing machine, the combination 45 of a main frame, a cutter bar hinged thereto to swing upwardly, driving mechanism for the cutters including a clutch, a hand lever pivoted on the main frame and operatively connected with the cutter bar for raising the 50 same, a clutch operating mechanism including a shiftable frame, and two projecting members with an idle space between them movable with the lever and acting when the lever is operated to engage the frame in succession and shift the same in the same direction in two successive movements, with a 55 pause between said movements to respectively disconnect the clutch and thereafter elevate the cutter bar to its full raised position.

3. In a mowing machine, the combination 60 of a main frame, a cutter bar hinged thereto to swing upwardly, driving mechanism for the cutters including a clutch, a hand lever pivoted to the main frame and operatively

connected with the cutter bar for raising the same, clutch operating mechanism including a shiftable frame, two projecting members with an idle space between them movable with the lever one in advance of the other, 70 the front member being in position to engage the shiftable frame and disconnect the clutch, the said idle space adapted to traverse the shiftable frame without moving it, and the rear member being in position to abut 75 against the shiftable frame after the clutch is disconnected, and after the lever has been moved to elevate the cutter bar to its full raised position, and means for locking the lever in position on the main frame with the 80 rear member engaged with the shiftable frame.

4. In a mowing machine, the combination of a main frame, a cutter bar hinged thereto to swing upwardly, driving mechanism for 85 the cutters including a clutch, a hand lever pivoted on the main frame and operatively connected with the cutter bar for raising the same, a clutch operating mechanism including a shiftable frame, and two projecting 90 spaced members movable with the lever one in advance of the other, the front member being in position to engage the shiftable frame and move the same to disconnect the clutch, and the rear member being in position to engage the shiftable frame after the clutch is disconnected and shift said frame idly in effecting the final raising movement of the cutter bar, said rear member engaging 95 the shifting frame at the end of its movement and serving to lock the clutch disengaged.

5. In a mowing machine, the combination of a main frame, a cutter bar hinged thereto to swing upwardly, driving mechanism for 100 the cutters including a clutch, a hand lever pivoted on the main frame and operatively connected with the cutter bar for raising and lowering the same, a clutch operating mechanism including a frame shiftable forwardly and rearwardly to respectively disconnect and connect the clutch, a front detent and a rear detent on said member, and a cam on the lever movable forwardly and backwardly in the operation of the lever, 110 said cam being formed with a toe and with a lug in rear of the toe, said toe and lug acting when the cam is moved forwardly, to engage the front detent in succession and shift the frame forwardly in two successive 115 movements.

6. In a mowing machine, the combination of a main frame, a cutter bar hinged thereto to swing upwardly, driving mechanism for the cutters including a clutch, a hand lever 120 pivoted on the main frame and operatively connected with the cutter bar for raising and lowering the same, a clutch operating mechanism including a frame shiftable forwardly and backwardly to respectively dis- 125

connect and connect the clutch, a cam movable with the lever, said cam being provided with a toe in position to engage the shiftable frame and disconnect the clutch when 5 the cam is moved forwardly, being provided with an idle space in rear of the toe adapted to traverse the shiftable frame without moving it and being provided also with a lug in rear of the toe at the rear end of the 10 idle space in position to abut against the shiftable frame after the clutch is disengaged and after the lever has been further moved to elevate the cutter bar to its final raised position, and means for locking the 15 lever in position on the main frame with the lug engaged with the shiftable frame.

7. In a mowing machine, the combination of a main frame, a cutter bar hinged thereto to swing upwardly, driving mechanism for 20 the cutters including a clutch, a hand lever pivoted on the main frame and operatively connected with the cutter bar for raising the same, a clutch operating mechanism including a shiftable frame movable forwardly to disconnect the clutch and movable in the same direction after the clutch is disconnected, and a cam movable with the lever and provided with a part in position to engage the shiftable frame and move the 30 same to disconnect the clutch, and provided with an idle space in rear of said part adapted to traverse the shiftable frame without moving it, and provided also with another part at the rear end of said idle 35 space in position to engage the said frame and move the same idly in the final raising movement of the cutter bar after the clutch is disconnected.

8. In a mowing machine, the combination 40 of a main frame, a cutter bar hinged thereto to swing upwardly, driving mechanism for the cutters including a clutch, a hand lever pivoted on the main frame and operatively connected with the cutter bar for raising 45 the same, a clutch operating mechanism including a shiftable frame, a front and a rear detent on said shiftable frame, and a cam movable with the lever, said cam

being provided with a toe and with a lug in position respectively to engage the front 50 detent in succession, and move the frame forwardly to disconnect the clutch, and said cam being provided also with a heel in position to engage the rear detent and shift the said frame rearwardly to connect the clutch. 55

9. In a mowing machine, the combination of a main frame, a cutter bar hinged thereto to swing upwardly, a driving mechanism for the cutters including a clutch, a hand lever pivoted on the main frame and operatively connected with the cutter bar for raising and lowering the same, a clutch operating mechanism including a shiftable frame, a front and a rear detent on said shiftable frame, and a cam movable with 60 the lever and provided with a toe and with a heel in position to engage the front and rear detent respectively, and shift the frame to respectively disconnect and connect the clutch, the rear detent being yieldable in 65 one direction to permit the heel to pass when the cam is moved to disconnect the clutch, and the front detent being yieldable in one direction to permit the toe to pass when the cam is moved in the opposite 70 direction to connect the clutch.

10. In a mowing machine, the combination of a main frame, a cutter bar hinged thereto to swing upwardly, a driving mechanism for the cutters including a 80 clutch, a hand lever pivoted to the main frame and operatively connected with the cutter bar for raising and lowering the same, a clutch operating mechanism including a shiftable frame, detents mounted at 85 the opposite ends of the shiftable frame, and a cam on the lever in position to co-operate with said detents in shifting the frame in opposite directions to respectively connect and disconnect the clutch, said detents being yieldable in one direction to permit the cam to pass one detent when it acts on the other.

In testimony whereof, I have affixed my signature.

ISAAC TROLLEY.
